AMPLIFIER

Robert W. Clark, Teaneck, N. J., assignor to Radio Corporation of America, a corporation of Delaware

Application November 29, 1941, Serial No. 420,961

7 Claims. (Cl. 179—171)

This invention relates to amplifiers and, in particular, to an electronic amplifier capable of amplifying a direct current as well as a very wide band of frequencies of alternating currents.

In many applications, including television, it is desirable to amplify concurrently direct current components as well as alternating current components of an exceedingly wide band of frequencies. The necessity for amplifying the direct current components requires a large number of separate power supplies or a single very high voltage supply, in known systems, each power supply being held constant within very narrow limits by suitable regulators. The requirements of extra separate power supplies and regulating equipment have militated against the use of direct current amplifiers, with the consequence that auxiliary circuits have had to be provided to reinsert components representative of the direct current components in an alternating current amplifier, which circuits are a compromise.

By my invention I overcome the necessity of providing a plurality of separate power supplies for a direct current amplifier, while, at the same time, I provide an amplifier whose response is substantially uniform for both direct current and alternating current components, even though the alternating current components may have frequencies extending to five megacycles per second. For the power supply, instead of using a large number of supplies or a single high voltage supply, this system will operate on one supply of voltage such as that normally used for audio amplifiers.

Accordingly, it is one of the objects of my invention to provide a new, useful and improved thermionic amplifier capable of amplifying both direct current and alternating current components over a wide band of frequencies.

Another object of my invention is to provide a direct current amplifier having a plurality of stages and requiring only a single power supply.

Another object of my invention is to provide a direct current amplifier capable of amplifying alternating currents over a wide band of frequencies and at the same time providing means for obtaining a very low impedance output circuit, while utilizing only a single power supply.

A still further object of my invention is to provide a direct current amplifier having but a single power supply and providing uniform gain for both direct current and alternating current components over a wide band, while remaining stable and relatively uninfluenced by fluctuation in the power supply.

Other objects of my invention will become apparent upon a reading of the following detailed description of my invention taken together with the drawing.

Figure 1 shows schematically a circuit diagram of a multi-stage amplifier embodying the principles of my invention, while Figure 2 shows a circuit diagram embodying a modification of the circuit arrangement shown in Figure 1, in which the modification includes means for driving an output from a low impedance circuit.

Turning now to Figure 1, I have shown by way of example a three-stage amplifier. It will be apparent from what follows, however, that the number of stages may be expanded or contracted in accordance with the requirements for a given use. The signal to be amplified, which may include direct current components as well as alternating current components of a wide band of frequencies, is applied to input terminals 1, across which terminals is connected a resistor 3. One side of the resistor is grounded, while the other side is connected to the control electrode of tube 5. The cathode of the tube 5 is connected through resistor 7 to ground, while the anode of tube 5 is connected to one end of the resistor 9. The other end of the resistor 9 is connected to resistor 11, which, in turn, is connected to the positive pole of the battery 39. The negative side of the battery is grounded. A condenser 13 is connected to the common junction point of the resistor 9 and resistor 11 and the other side of the condenser is grounded. Connected between the anode of the tube 5 and the grid of the tube 21 is a parallelly connected resistor 17 and condenser 15. From the junction point of the resistor 11 and the grid of the tube 21 is connected a resistor 19, the other terminal of which is grounded. The cathode of tube 21 is connected through the grounded cathode resistor 22, while the anode of the tube 21 is connected to the serially connected resistors 23 and 25. The other terminal of the resistor 25 is connected to the plus terminal of the battery 39. A condenser 27 is connected to the junction point of the resistors 23 and 25. The tube 33 has its grid coupled to the anode of the tube 21 through the parallelly connected resistor 31 and condenser 29, and the grid of tube 33 is connected to ground through the resistor 32. The load circuit 35 is connected between the anode of tube 33 and the positive terminal of the battery 39. The cathode of tube 33 is connected to ground through the resistor 31.

In operation, the signals impressed on the grid of tube 5 will be amplified by the tube in accord-

ance with well known theory of operation of thermionic amplifiers. The resistor 7 is so chosen in value as to provide appropriate bias to the tube 5 so that the tube operates on the linear portion of its grid voltage-plate current characteristic. The amplified voltage which appears across the serially connected resistors 9 and 11 is then transferred to the grid circuit of tube 21 for further amplification and the amplified output of the tube 21 is further amplified by the tube 33 and sent to the load circuit 35. In order that the tubes 21 and 23 may operate on the linear portion of their characteristics, it is necessary that the potential drop between the grid and the cathode, in general, be negative and of a value which falls midway on the linear portion of the grid voltage-plate current characteristic of the tubes 21 and 23. These conditions can be met by proper choice of resistances 19 and 20 since E_{21} is equal to E_{19} minus $I_{21}R_{22}$; where E_{21} is equal to the potential difference between the grid and cathode of tube 21, E_{19} is the potential drop across the resistor 19; I_{21} is the plate current of the tube 21, while R_{22} is the resistance of the resistor 22.

It will be noted that the potential at the junction point of the grid of tube 21 and the resistor 19 is positive with respect to ground, while the cathode of tube 21 is also positive with respect to ground. By insuring that the potential drop across the resistor 22 is greater than the potential drop across the resistor 19, the grid of tube 21 will be negative with respect to the cathode of tube 21. Similar consideration holds for the tube 33.

In order that the amplification for the direct current, low frequency alternating current, and the high frequency alternating current components shall be constant, it is necessary that the following relationship be maintained for the tubes 5 and 21:

$$\frac{R_{19}}{R_9} = \frac{R_{17}}{R_{11}} = \frac{C_{13}}{C_{15}}$$

where the subscripts refer to the elements shown in Figure 1. Under these conditions, uniform amplification of the entire band from zero to very high frequencies will be obtained, and, at the same time, the phase angle will remain substantially linear as a function of frequency so that completely uniform amplification over the entire band, including the direct current components, is obtained. Similar ratios for the stage following the tube 21 are necessary and become:

$$\frac{R_{22}}{R_{23}} = \frac{R_{21}}{R_{25}} = \frac{C_{27}}{C_{29}}$$

It will be noted that when the values are so chosen in the ratios given above that at very low frequencies the load impedance becomes substantially the sum of the resistors 9 and 11 and 23 and 25, respectively, but the transferred voltage to the grids of tubes 21 and 23, respectively, is diminished and is equal to, in the case of tube 21:

$$\frac{R_{19}}{R_{17} + R_{19}}$$

while, in the case of tube 33, is:

$$\frac{R_{22}}{R_{21} + R_{22}}$$

Because of the selected ratios, it will be readily apparent that the actual voltage transfer be-

comes the inverse of the sum of the plate load impedances. At very high frequencies the condensers 13 and 15, for example, become substantially zero impedance so that the entire voltage of the resistor 9 is transferred to the grid of the tube 21 so that uniform amplification results.

It will thus be apparent that only a single voltage supply is necessary for providing uniform amplification of a multi-stage amplifier of both the direct current and alternating current components. Moreover, small fluctuation in the supply voltage of the battery 39 will not introduce disturbances, since the voltage rise in the plate circuit is counterbalanced by the change of voltage in the grid circuit, due to the change in potential across the cathode resistors, so that stable operation is afforded.

In Figure 2, I have shown a modification of the embodiment of my invention shown in Figure 1, whereby with a relatively small change in the circuit arrangement I make it possible to obtain a low impedance output circuit, which impedance output circuit may be made independent of any requirements in the amplifier. For purposes of illustration, in Figure 2 I have shown but two stages, one stage being an amplifier stage similar to the stages shown in Figure 1, while the output stage comprising the tube 79 includes the modification of a low impedance output circuit. In Figure 2 the signals to be amplified, containing both direct current and alternating current components, are impressed on the terminals 51 across the grid cathode circuit of the tube 55. A high impedance 53 serves to prevent the grid cathode circuit from being opened in the event that the source of signals is disconnected from the terminals 51. A cathode resistor 57 is connected between ground and the cathode of tube 55. The plate circuit of tube 55 comprises the serially connected resistors 59 and 61 with a decoupling capacity 63 connected effectively across the filter resistor 61. Coupling to the tube 79 is provided by way of the parallelly connected resistor and capacitor 67 and 65, respectively, and a grid leak resistor 71, connected between the grid of the tube 79 and ground, is provided in order to supply the amplified potentials from the tube 55 to the grid cathode circuit of the tube 79. A resistor 69 connected between the junction point of the parallelly connected capacitor 65 and resistor 67 and the grid of the tube 79 to the single power supply 71 serves to provide proper bias to the grid of the tube 79 by means of the variable tap 75 of the potentiometer 73. It will be noted that by this connection the cathode resistor 81 connected between the cathode of the tube 79 and ground may be any value desired, without upsetting the grid bias of tube 79, since the grid bias may be set independently by the potentiometer tap 75. The plate of the tube 79 is supplied with power through the resistor 83, and a decoupling condenser 85 serves to maintain the potential of the plate of the tube 79 substantially constant.

Output is obtained across the cathode resistor 81 by means of terminals 87. In view of the fact that the cathode resistor 81 may have any value, a low value may be selected in order to feed, for example, a coaxial cable whose impedance may be of the order of 75 ohms. By making the cathode resistor 81 seventy-five ohms, perfect termination match is afforded so that reflections in the cable are avoided.

In the circuit shown in Figure 2, in order that

the amplification remain constant, it is necessary that the following relationships exist:

$$\frac{R_{69}R_{77}}{R_{59}(R_{69}+R_{77})}$$

must equal R_{67}/R_{61} , which, in turn, must equal C_{63}/C_{65} , where the R's and the C's representing the elements in Figure 2 correspond to the subscripts. Ordinarily, the resistors 69 and 67 may be suitably chosen to provide the proper grid bias to the grid of the tube 79, cooperating with the setting of the potentiometer 73.

It will be appreciated that where extremely high frequencies of the order of five megacycles are desired to be amplified linearly, series "peaking coils" may be inserted to overcome stray capacities in series with the resistors 9 and 23, in Figure 1, and in series with the resistor 59 in Figure 2. Such peaking coil circuits are, of course, well known in the art, and, accordingly, are not illustrated here. The patent to Preisman No. 2,243,121, issued on May 27, 1941, for example, shows the use of peaking coils. It will be understood that for high frequencies the plate circuits may employ "shunt peaking" circuits or any other of the well-known circuits which afford constant impedance over wide bands of frequencies.

Various alterations and modifications of the present invention may become apparent to those skilled in the art and it is to be noted particularly that while triodes have been shown in the drawing merely by way of example, that tetrodes, pentodes, or any other type of thermionic amplifying tubes may be used, and in practice the pentode is ordinarily preferred, since it provides a constant current generator of signals, which is particularly suited for use in my invention. Thus any and all such modifications and alterations are to be considered within the purview of the present invention except as limited by the hereinafter appended claims.

Having now described my invention, what I claim is:

1. An amplifier comprising a plurality of thermionic tubes, each tube having at least a cathode, a control electrode and an anode, a single source of direct current potential, two serially connected resistors connected between the anode of one of said tubes and the positive terminal of said source, a condenser connected between the junction point of said serially connected resistors and a common point of potential with respect to said positive terminal, a parallelly connected resistor and condenser coupling the said anode to the grid of another of said plurality of tubes, means including a resistor connected between the negative terminal of said source of potential and said grid to maintain proper bias on said grid, a resistor connected between said common point and the cathode of said other tube, an anode circuit connected between said positive terminal and the anode of said other tube and means to supply signals to the grid-cathode circuit of said first-named tube.

2. An amplifier comprising a plurality of thermionic tubes, each tube having at least a cathode, a control electrode and an anode, a single source of direct current potential, two serially connected resistors connected between the anode of one of said tubes and the positive terminal of said source, a condenser connected between the junction point of said serially connected resistors and the negative terminal of said source, a parallelly connected resistor and

condenser coupling the said anode to the grid of another of said plurality of tubes, a resistor connected between the negative terminal of said source of potential and said grid, a resistor connected between said negative terminal and the cathode of said other tube, an anode circuit connected between said positive terminal and the anode of said other tube and means to supply signals to the grid cathode circuit of said first-named tube.

3. An amplifier comprising a plurality of thermionic tubes, each tube having at least a cathode, a control electrode and an anode, a single source of direct current potential, two serially connected resistors connected between the anode of one of said tubes and the positive terminal of said source, a condenser connected between the junction point of said serially connected resistors and a common point of potential with respect to said positive terminal, a parallelly connected resistor and condenser coupling the said anode to the grid of another of said plurality of tubes, a resistor connected between said common point and said grid, a resistor connected between the negative terminal of said source of potential and said grid, a resistor connected between said common point and the cathode of said other tube, an anode circuit connected between said positive terminal and the anode of said other tube and means to supply signals to the grid cathode circuit of said first-named tube.

4. An amplifier comprising a plurality of thermionic tubes, each tube having at least a cathode, a control electrode and an anode, a single source of direct current potential, two serially connected resistors connected between the anode of one of said tubes and the positive terminal of said source, a condenser connected between the junction point of said serially connected resistors and a common point of potential with respect to said positive terminal, a parallelly connected resistor and condenser coupling the said anode to the grid of another of said plurality of tubes, a resistor connected between said common point and said grid, a resistor connected between the negative terminal of said source of potential and said grid, a resistor connected between said common point and the cathode of said other tube, an anode circuit connected between said positive terminal and the anode of said other tube and means to derive output energy from across said resistor connected to said cathode.

5. An amplifier comprising a plurality of thermionic tubes, each tube having at least a cathode, a control electrode and an anode, a single source of direct current potential, two serially connected resistors connected between the anode of one of said tubes and the positive terminal of said source, a condenser connected between the junction point of said serially connected resistors and the negative terminal of said source, a parallelly connected resistor and condenser coupling the said anode to the grid of another of said plurality of tubes, a resistor connected between the negative terminal of said source of potential and said grid, a resistor connected between said negative terminal and the cathode of said other tube, an anode circuit connected between said positive terminal and the anode of said other tube and means to supply signals to the grid cathode circuit of said first-named tube, the ratio of said grid-connected resistor to said anode-connected resistor being equal to the ratio of said junction-point connected condenser to said parallel-connected con-

denser and equal to the ratio of said coupling resistor to said positive-terminal connected resistor.

6. An amplifier comprising a plurality of thermionic tubes, each tube having at least a cathode, a control electrode and an anode, a single source of direct current potential, two serially connected resistors connected between the anode of one of said tubes and the positive terminal of said source, a condenser connected between the junction point of said serially connected resistors and a common point of potential with respect to said positive terminal, a parallelly connected resistor and condenser coupling the said anode to the grid of another of said plurality of tubes, a resistor connected between said common point and said grid, a resistor connected between the negative terminal of said source of potential and said grid, a resistor connected between said common point and the cathode of said other tube, an anode circuit connected between said positive terminal and the anode of said other tube, means to supply signals to the grid cathode circuit of said first-named tube, and a load circuit connected across said resistor connected to said cathode, the ratio of capacity of said first-named condenser to the capacity of said second-named condenser being equal to both the ratio of said coupling resistor to said positive-terminal connected resistor and the ratio of the effective resistance of the two grid connected resistors in parallel to said anode-connected resistor.

7. An amplifier comprising a first and second

electron discharge tube each having at least a cathode, a control electrode and an anode, a single source of direct current potential, means to apply potential variations between the control electrode and cathode of said first tube, a first and second resistance connected in series between the positive terminal of the source of potential and the anode of said first tube, a coupling resistance connected between the anode of said first tube and the control electrode of said second tube, a grid resistance connected between the control electrode of said second tube and the negative terminal of the source of potential, a first condenser connected in parallel with said coupling resistance, a second condenser connected between the junction of the first and second resistances and the negative terminal of the source of potential, biasing means connected between the negative terminal of the source of potential and the cathode of said second tube, means including said source of potential for maintaining the anode of said second tube positive with respect to its associated cathode, the values of the resistances and condensers being so chosen that the ratio of the grid resistance to the second resistance equals the ratio of the coupling resistance to the first resistance and equals the ratio of the second condenser to the first condenser, whereby a wide band of frequencies extending from zero to at least five megacycles per second can be amplified substantially linearly and without phase shift.

ROBERT W. CLARK.
